S. J. DUNKLEY,

PEACH PITTING TOOL.

APPLICATION FILED JAN. 28, 1919

1,374,288.

Patented Apr. 12, 1921.

UNITED STATES PATENT OFFICE.

SAMUEL J. DUNKLEY, OF KALAMAZOO, MICHIGAN, ASSIGNOR TO DUNKLEY COMPANY,
OF KALAMAZOO, MICHIGAN, A CORPORATION OF MICHIGAN.

PEACH-PITTING TOOL.

1,374,288.

Specification of Letters Patent. Patented Apr. 12, 1921.

Application filed January 28, 1919. Serial No. 273,590.

To all whom it may concern:

Be it known that I, SAMUEL J. DUNKLEY, a citizen of the United States, residing at Kalamazoo, Michigan, have invented certain 5 new and useful Improvements in Peach-Pitting Tools, of which the following is a specification.

This invention relates to improvements in peach pitting tools.

10 The main object of the invention is to provide a simple and effective rotary cutting tool for the cutting out of pits from cling stone peaches, although the tool is adapted for various purposes, and can be very well 15 used for taking the cores from pears and apples.

Objects relating to details and economies of construction and operation will appear from the detailed description to follow.

20 I accomplish the objects of my invention by the devices and means described in the following specification. The invention is clearly defined and pointed out in the claim.

A structure which is a preferred embodiment of my invention is fully illustrated in the accompanying drawing forming a part 25 of this specification, in which:

Figure I is a longitudinal central sectional view through a tool embodying the features 30 of my invention, the driving shaft and some of the gears and other parts being shown in full lines, the same being taken on a line corresponding to line 1—1 of Fig. II.

Fig. II is a detail transverse sectional 35 view on line 2—2 of Figs. I and V, the gears, shafts and cutting tools being shown in full lines.

Fig. III is a detail view of the spanner wrench for removing and inserting the gears 40 for cleaning and inspection.

Fig. IV is a detail view of a modification of the cutter.

Fig. V is a detail view of the tool modified for support in a vise or clamp to permit 45 the operator to use both hands in handling the fruit.

Fig. VI is an enlarged detail view of a modification of the knife 14, showing the serrated edge.

50 In the drawings the sectional views are taken looking in the direction of the little arrows at the ends of the section lines and similar numerals of reference refer to similar parts throughout the several views.

Considering the numbered parts of the 55 drawing, 1 is the handle, on which is supported the detachable head 2, the same being provided with a screw thread connection 3 with a bushing 6 which provides a journal bearing for the driving shaft 4. A 60 suitable bushing connection 5 is provided for the flexible shaft 7 at the opposite end of the handle.

A beveled gear 8 is provided on the end of the shaft 4 and intermeshes with a gear 65 9 which drives the revoluble cutter 14. A removable plug 10 carrying a sleeve 11 is provided to support the tubular shaft 13 which carries the cutting tool 14. The cutting tool 14 is hollow and conical in form 70 with the outer sides beveled at 14' as indicated. The tool is provided with a shank 15 from the conical tip end which is inserted into the tubular shaft 13 and retained there by a set screw 16, as clearly appears 7 in Fig. I. The tool is readily removed by withdrawing the screw 16. The entire head 15 can be disassembled for cleaning and inspection by using the spanner wrench 17, as the parts are readily removable for cleaning 80 and lubrication.

In Fig. IV, I have indicated a modification of the cutter. The same is still of the conical form with the beveled cutting edge, with portions cut away at 19 to permit of 85 the ready passing of the debris, such as halved pits or the parts of the core of any fruit.

It is sometimes desirable for instance 90 where fruit is large or is particularly tough for the operator to use both hands, in which event I provide the handle with a suitable squared portion 20 which can be supported in a clamp or vise 21 as indicated in Fig. V. It may of course have any suitable support. 95

I have shown my improved pitting and coring tool in its most approved form, but desire to state that it can be considerably varied in details without departing from my 100 invention. While it is desirable that this cutter be disposed in transverse relation as indicated, it of course might very readily be supported on the end of the shaft and the intermediate gearing be avoided. As 105 this is such an obvious expedient, I have not deemed it necessary to illustrate it.

Having thus described my invention, what

I claim as new and desire to secure by Letters Patent is:

In a pitting or coring tool, the combination of a suitable handle, an axially disposed driving shaft therein, a head on the handle with a transversely disposed shaft, a hollow conical cutting tool with shank from the apex and with peripheral cutting edge beveled from the outside carried by the said

driven shaft, coating substantially as described for the purpose specified.

In witness whereof, I have hereunto set my hand and seal in the presence of two witnesses.

SAMUEL J. DUNKLEY. [L.S.]

Witnesses:

LUELLA GREENFIELD,
MARTHA J. GREGORY.
